APERTURE CARDS

John F. Langan and Glen P. Robinson, Jr., Atlanta, Ga., assignors to Langan Aperture Cards, Inc., Greenvale, N.Y., a corporation of Delaware

Filed Aug. 6, 1962, Ser. No. 214,928
1 Claim. (Cl. 40—158)

This invention relates to improvements in cards adapted for mounting projectable transparencies such as for example film record cards in which individual microfilm sections are mounted to facilitate the handling, filing and storage of the transparencies, and also the sorting out, projecting and if desired the reproducing of individual transparencies when desired. The invention relates especially to novel blank cards adapted for such uses and to their manufacture.

The invention is particularly useful in mounting microfilm sections in cards that are capable of being sorted mechanically, although it is not limited to this use as explained hereinafter. Various types of mechanical sorting systems are well known. They range from systems in which groups of related cards can be separated and extracted from a stack by inserting a pin or like instrument through aligned holes in the edges of the cards, to the elaborate and well known IBM system in which the cards are perforated according to a code and are sorted by electrically controlled apparatus responsive to the location of the perforations in the individual cards. However, the invention also comprehends the mounting of projectable transparencies, including all types of photographic film records, in ordinary file cards, catalog cards, and the like.

With reference to machine sorting of the IBM type, the present invention comprises important improvements of the "punch cards" or "aperture cards" disclosed in the prior Langan Patents Nos. 2,511,859, 2,512,106 and 2,587,022, as well as in the preparation and use of such cards. Aperture cards of the type shown in these prior patents have been very widely used, especially by the United States Government. By way of example, a recent program of standardization of the preparation and distribution of engineering data by this system, such as drawings, specifications and the like, in one particular Government field is estimated to require 90 million aperture cards initially and average annual usage thereafter of 15 million aperture cards.

The merit of such aperture card system is attested by their widespread adoption and successful use, in spite of serious defects of prior systems which are corrected by the present invention. One such defect has had to do with the "blank" cards as supplied heretofore in bulk quantity to the ultimate user, i.e., before the film is mounted therein. As disclosed in the prior Langan Patent No. 2,511,859 mentioned above, these blank cards are distributed with the aperture already formed and with a strip of pressure-sensitive adhesive material secured to the backside of the card around the edges of the aperture, a narrow section of this strip extending into the aperture with exposed adhesive thereon for subsequent mounting of a transparency in the aperture. This exposed adhesive is covered by a temporary sheet of glassine paper or similar material.

In the first place, such "blank" cards cannot ordinarily be furnished to a prospective user in large supply because they must be used within a relatively short period or else the adhesive deteriorates to the point where adequate bonding of the transparency cannot be secured. In large part because of this inability to store reserve supplies of blank cards, the common practice has been for the customer to send his microfilm to a central service center

2

where the individual film sections are mounted in the cards. The fact that the customer cannot cut out and mount sections himself, as and when desired, has heretofore made for inflexibility in the use of the aperture cards and has detracted seriously from the utility and desirability of aperture card systems.

The factor mentioned above also makes it practically impossible to use aperture cards for mounting two or more sequential transparencies on the same card, as is often desirable in order to "post" a record of successive stages of development of a project. In such cases, it is desirable to mount the first transparency in one aperture of a card, and to be able to supplement the original record by mounting a second transparency at some later date in a second aperture of the same card. Using cards of the type heretofore used, however, when the time came for mounting the second transparency, the pressure-sensitive adhesive material around the second aperture would no longer be effective so that a separate card would have to be used.

Another problem arises from frequent sticking together of adjacent cards due either to exposed pressure-sensitive adhesive in the case of imperfect preparation, or to "bleeding" of the pressure-sensitive adhesive material from underneath the edges of the protective glassine cover sheet or the edges of the transparency itself. In such cases the separation of blank cards for perforation according to a mechanical sorting code, or for the operations of mounting sections of film therein, or during subsequent use of the finished cards for machine sorting, projection, and the like, is hindered to an extent which militates seriously against the usefulness of such systems.

Furthermore, any increase in thickness of such cards is very undesirable. Even though an applied strip of adhesive may only increase the thickness of a card by an extremely small amount, say $\frac{1}{1000}$ of an inch, still when a deck of 1000 or more cards are stacked in a file drawer as is often the case, there will be a difference of an inch or more in the length of one side of the stack as compared with the other.

Still further objections to prior systems arise from the fact that the operations involved in preparing the blank cards, i.e., punching out the apertures and then applying the adhesive strips and the cover sheets, as well as the operations involved in finishing the cards including stripping off the cover sheets and disposing of them and then applying the transparencies to the exposed adhesive strips, both require objectionably elaborate and expensive apparatus such as illustrated for example in the prior Standish Patent No. 2,666,543, the prior Morrison Patents Nos. 2,493,159, and 2,560,301, and the prior Baker Patent No. 2,643,786. Many users of aperture cards have only a relatively small number of transparencies to be mounted at one time, and this only sporadically, so that they cannot justify the expense of purchasing and maintaining such elaborate equipment but must again rely on service centers such as mentioned above.

But perhaps a more basic objection is that the bond between the transparency and the card is not secure enough in many cases. For example, under ordinary conditions of usage, a deck comprising say 1000 cards bearing microfilmed engineering drawings should last for years despite repeated handling incident to removing the card from and returning them to the drawer, riffling decks of cards before placing them in sorting machines, handling individual cards in projection machines, print copiers, and the like, etc. In the course of such manipulations, the cards are repeatedly subjected to twisting and bending from all angles. Unless the bond between the film section and the card is continuous, strong, and permanent, separation of the film from the adhesive may eventually

occur with the result that the card must be thrown away and the film section re-mounted in a fresh blank card.

Added to the above disadvantages is the fact that even though the aperture in the blank card is covered by a temporary removable cover sheet, still the presence of the aperture is undesirable for various reasons. It obviously detracts from the mechanical strength of the blank card, and it may interfere with and hinder the perforation of the card for mechanical sorting before the transparency is mounted.

Various attempts have been made to eliminate the use of such pressure-sensitive adhesives and to remedy the defects mentioned. By way of example, the prior Langan Patent No. 2,587,022 suggests heat bonding of thermoplastic materials to the card, proposing to cover the aperture with a sheet of cellulose acetate and to bond its edges by heat and pressure to the edges of the card around the aperture. The material of this cover sheet was proposed to be the same as or similar to that of the base of the film itself, with the thought that subsequently the film section and the cover sheet could be united integrally by heat and pressure to form a unitary transparency across the aperture. Usually heat damage to the film resulted, however, such as clouding and/or buckling or warping of the film. Moreover, the bond formed by heating the cellulose acetate cover sheet and pressing it into contact with the card, or by doing the same thing to the edges of the cellulose acetate base of the film itself as suggested in the prior Langan Patent 2,633,655, was unsatisfactory. If the degree of heat was only enough to soften the cellulose acetate it would not penetrate the fibers of the card and the bond was weak and unsatisfactory. Attempts to increase fluidity by raising the temperature usually caused warping or buckling of the card itself.

A step toward the elimination of the above difficulties has been disclosed and claimed in the copending application of John F. Langan, Serial No. 70,814, filed November 21, 1960, and entitled Aperture Card System. As disclosed in this prior application, the strength of the eventual bond between the film and the card is materially increased by applying a solution of thermoplastic material to the card so that it soaks into the card fibers. Accordingly when the solvent dries out, the thermoplastic solute is left not only on the surface of the card but also beneath its surface and distributed on and among the fibers of the card structure. Then when the bond is ultimately formed, this thermoplastic material and the thermoplastic film base as well are softened by heat so as to become tacky and merge or weld together under pressure to join the film to the card with a bond strength that is much higher than can be obtained by mere surface adhesion. It has been found, however, that the heat required to secure effective welding is still excessive and that warping or other damage to the card usually results.

One solution of the foregoing problems is disclosed and claimed in the copending application of John F. Langan, Lorimer Clayton, Jr., and Grant E. Allen, Jr., Serial No. 191,117, filed April 30, 1962. In this case the bond between the film section and the card is formed by an adhesive carried by the card which is dry and non-sticky or non-tacky at ordinary temperatures but becomes tacky and adhesive at temperatures approaching 200° F. and above. Thus the amount of heat required to effect good bonding is so limited that damage to the card is avoided. At the same time, however, there is no material softening and/or plastic deformation of the film itself and therefore other provisions must be made to prevent an impermissible increase in thickness of the combined card and film. This is prevented by a special grinding procedure that constitutes a part of the invention of said application Serial No. 191,117, and is also utilized in the present invention as will now be described.

Preferably (but not necessarily as pointed out below) the first step in the present invention is to indent one side of the card around the outline of the aperture eventually to be cut therein, so as to form a trench-like depres-

sion in one face of the card and a corresponding ridge-like projection embossed on the opposite surface of the card. It will be apparent that this stamping or embossing operation can be performed by any suitable type of reciprocating or rotating die mechanism. While it has been proposed heretofore to pre-dimple such cards by compressing the edges of the aperture, as for example in the prior Patent No. 2,633,655, the extent of such dimpling that can be produced merely by compression, without embossing the opposite side of the card, is limited

10 by the compressibility of the card material and as a practical matter a depression of say 0.001-0.002 inch is about the maximum that can be realized with the usual card having an initial thickness of approximately 0.0067 inch. 15 Such depressions are not of sufficient depth to accommodate the thickness of the film (varying from about 0.003 about 0.0055 inch) and accordingly a very large amount of thinning of the margins of the film by plastic flow and deformation is required in order to approach the desired 20 final condition illustrated in said prior patent. According to the present invention, on the other hand, grooving or indentation of the card on one side can easily be made much deeper by permitting the card to be embossed on the other side, the stamping or embossing operation producing a sort of bending or folding of the card material 25 instead of compression thereof.

The next step according to the present invention is to remove the ridge-like embossed projection from the opposite surface of the card in any suitable manner so as to restore the surface on this side of the card to a planar condition. This can be accomplished by any suitable cutting or shaving operation, but most conveniently by high speed grinding or abrasion applied to the cards while moving relatively past the grinding device. This produces 30 a card which is substantially planar over one side, and is planar on the other side as well except that around the outline of the aperture eventually to be cut out, there is a trench-like depression the bottom of which is formed by a thin web of card material. When the portion of the 35 card surrounded by this trench is eventually cut out to form the aperture, the combined thickness of the film and of the ledge around the aperture (which ledge previously formed the bottom of the groove) is not materially, if any, more than the thickness of the card. By way of example, a card initially 0.0067 inch thick may be embossed and ground to a web thickness of about 0.015-0.002 inch in the bottom of the trench around the aperture and the added thickness of the usual silver halide film of 40 say 0.0055 inch makes a total of around 0.007 inch.

It will be understood that the depth to which the blank 45 cards are stamped or embossed, and the corresponding thickness of the card material at the bottom of the groove may vary depending upon the kind of film to be mounted, the web being for example from about 0.004 inch to about 0.002 inch or less for film varying in thickness within the 50 range stated above.

In cards of the type disclosed in the aforesaid application Serial No. 191,117, the heat-activatable adhesive is applied to the thinned strip-form sections of the card which are formed by the above embossing and grinding operations. When it comes to the operation of mounting the film section, the aperture in the card is first cut out, after which the film section is placed in registry with the aperture and with its edges overlapping the adhesive-coated thin ledges around the aperture, then the film and card are pressed together around the overlapping edges 55 while at the same time just enough heat is applied to activate the adhesive. Excellent results have been attained in this way, but still it is desirable in the interest of simplification of mounting equipment and of the mounting operation to dispense with the use of heat altogether. The aforesaid application Serial No. 191,117 discloses activation of the adhesive by the addition of a solvent at the time of bonding, but this method also involves undesirable complications.

The chief object of the present invention is to provide

a novel card of the type described which meets the requirements set forth above and in which the adhesive can be activated to mount the film without the use of any heat or the addition of any solvent whatsoever, and preferably by the application of pressure alone.

To the above ends, the present invention makes use of so-called encapsulated adhesives of the type prepared by methods such as are disclosed in U.S. Patents Nos. 2,800,457 and 2,800,458 (Reissue No. 24,899), both granted November 29, 1960, to Barrett K. Green. Typical products prepared by such methods are disclosed in U.S. Patents Nos. 2,907,682, 2,986,477, 2,988,460 and 2,988,461 to Herman J. Eichel. In such cases the application of pressure ruptures the capsules and releases materials which provide a tacky adhesive in various ways, such as combinations of adhesives and activating solvents, adhesive materials which require subsequent heating to become effective, adhesive materials which are or become flowable upon release and then set or dry to form a permanent bond, etc. As used hereinafter, the term "pressure-rupturable encapsulated adhesive" refers generically to adhesives of the type illustrated in and by the Green and Eichel patents, although it will be understood from what has been said above that for most purposes those materials which do not require heat are preferred. The capsules are formed in a liquid carrier, forming a suspension or slurry which may be coated on a desired article and dried, leaving an adherent layer of pressure-rupturable capsules.

Heretofore the use of such pressure-rupturable encapsulated adhesives on aperture cards has been precluded for practical reasons. Manual handling of the cards, or passing them through coding and/or punching machines, was apt to cause at least some of the capsules to rupture prematurely and consequently the cards were apt to stick together. Even pressures due to the weight of stacked cards in storage could cause premature rupture and consequent "blocking" of the cards.

In the present invention, however, the narrow trench-like depressions formed by embossing and grinding, on the order of $\frac{1}{8}$ " in width and 0.004-0.005" in depth, act as receptacles in which a layer of pressure-rupturable encapsulated adhesive of the width of the trench and on the order of 0.002-0.003" in thickness can be deposited with its exposed upper surface lying below the plane of the card surface and thereby protected against premature rupture from causes such as stacking weights and pressures, scraping effects during mechanical handling, and the like.

For mounting, the portion of the card that is outlined and surrounded by the adhesive-containing trenches is removed in any suitable manner, for example, by a suitable punching operation, thereby forming an aperture in the card surrounded by their adhesive-coated ledges as already described. When the film section is in place, it is only necessary to apply enough pressure to rupture the capsules and release and/or activate the adhesive.

One embodiment of the invention has been illustrated diagrammatically in the accompanying drawings, but it is to be expressly understood that said drawings are for purposes of illustration only and are not to be taken as a definition of the limits of the invention, reference being had to the appended claim for this purpose.

In the drawings,

FIG. 1 is a diagrammatic illustration of the sequence of steps involved in preparing blank cards embodying the present invention in automated manner;

FIG. 2 is a plan view of one of the finished blank cards;

FIG. 3 is a section on the line 3-3 of FIG. 2;

FIGS. 4 and 5 are sectional views corresponding to FIG. 3 but showing subsequent successive steps in the completion of the blank cards;

FIG. 6 illustrates diagrammatically the step of cutting out the aperture in a blank card;

FIG. 7 shows the operation of bonding a section of film in place on the card; and

FIG. 8 shows the completed card with the film mounted therein.

Referring first to FIG. 1, a stack of cards to be processed is indicated by the numeral 1 at the left hand side of the figure. For example, these cards may be "punch" cards of the usual type employed with the IBM system of tabulating card machines, being formed of card stock having a specified thickness of 0.0067 inch with a tolerance of plus or minus 0.0004 inch. As will be understood, the stack of cards can be supported in any suitable magazine from which the cards are fed one by one in succession from the bottom of the stack in the direction indicated by the arrow 2, such feeding mechanisms being well known in the art.

As already stated, the first step according to the present invention comprises an embossing or stamping operation. When the cards are to be printed, this embossing operation can be combined with the printing press if desired so that the printed cards leave the press in embossed condition, but as here shown for purposes of illustration, the embossing operation is performed by passing the cards longitudinally in succession between the upper embossing roller 3 and a lower backing roller 4 of rubber or the like. One of the cards is shown at 5 as it passes between these rollers and is embossed in the desired pattern by means of dies 6 carried by the roller 3 at peripheral intervals corresponding with the rate of feed of cards 5.

A detailed diagrammatic view of one of these embossing dies is shown in FIG. 1A. It comprises raised ribs 7 extending circumferentially of the roller 3 and parallel to but spaced from one another, the ends of these ribs being cross-connected by transverse ribs 8 so that the ribs together form a rectangular outline to be embossed on the card 5. Of course, other shapes may be desirable. The height of the ribs 7 and 8 will obviously be predetermined so as to produce embossing of the desired depth, depending upon the thickness of the film to be mounted and to some extent also on the yieldability of the rubber backing roller 4. It will be evident that a similar die arrangement can be provided on a conventional reciprocating stamping die.

Having been embossed, the cards pass from the rollers 3, 4 to a second set of rollers 9 and 10 which accomplish the operation of removing the embossed ridges from the back of the card as described above. In order to provide the desired support against the pressure of the operative lower wheel 10, the upper wheel 9 carries a series of die-like supports 11 similar in size and shape to the dies 6 of the roller 3. The grinding wheel, by way of example, may be an aluminum oxide wheel running at a surface or linear peripheral speed of approximately 2300 feet per minute, having a wheel grit size of 46-60 and wheel hardness in the range of G to J (the letters at the beginning of the alphabet indicating softer grades). Of course, these values are not critical; for example, the linear peripheral speed of the grinding wheel may vary between approximate limits of 1800 feet per minute and 3000 feet per minute.

Referring to FIG. 3, the depth of embossing by the dies 6 may be approximately 0.0045 inch, in the case of relatively thick film such as the usual silver halide film which approximates 0.0055 inch. In such a case, the height of the ribs forming the dies 6 at supports 11 should be somewhat higher, say in the range of 0.006 inch to 0.01 inch. In passing between the rollers 9 and 10, therefore, as explained above, converting it from the condition shown in FIG. 3 to that shown in FIG. 4 and leaving a web thickness of about 0.002 inch.

For the purpose of applying the coating of pressure-rupturable encapsulated adhesive, it will be desirable of course to employ mechanical devices. FIG. 1 shows dia-

grammatically a backing roll 12 and a printing roller 13 between which the cards 5 pass in succession, the roller carrying suitable means 14 such as a pad, or wick arranged to apply the adhesive material in a pattern corresponding with the pattern of embossing and grinding previously performed. Any suitable type of adhesive supply can be employed, and for purposes of illustration FIG. 1 shows a supply roller 15 rotating partially submerged in a bath 16 of the adhesive slurry and transferring this slurry to the applicator means 14.

Following the application of the adhesive slurry, which dries rapidly (this can be hastened by conventional means such as hot air blasts, infra-red radiation or the like), the cards 5 pass to any suitable receptacle here shown as a stack 17.

FIG. 3, as already noted, shows the condition of the blank cards after having passed between rollers 3 and 4. During this passage, die members 6 create an indented groove 18 on one side of the card and a corresponding ridge-like projection 19 on the other side. As will be understood from the foregoing general description, the groove 18 may be approximately $\frac{1}{8}$ inch wide and follows the rectangular outline of the aperture eventually to be cut in the card.

The card 5 next passes between the wheels 9 and 10, where its condition progresses to that shown in FIG. 4 wherein the ridge-like projections 19 of FIG. 3 have been ground away, leaving the thin webs 20 forming the bottom of said grooves and connecting the surrounding major portion of the card indicated at 21 with the rectangular section 22 which is eventually to be removed to form the aperture. As already pointed out, these webs 20 may be as little as 0.0015 inch to 0.002 inch, and while they are quite narrow (usually 0.125 inch), nevertheless in the condition shown in FIG. 4 they may be too weak for safety in storage, distribution and handling of such cards before the film is actually inserted therein. Application and drying of the adhesive slurry results in building up a relatively thin but substantially continuous external layer of solid pressure-rupturable encapsulated adhesive indicated at 23. As a result, the inherently weak thin webs 20 are substantially strengthened to withstand all normal conditions of use of the blank cards, including not only manual handling but often the punching of said cards by machine according to desired machine sorting codes, etc. At the same time these webs are pushed in by the applicators 14 as shown in FIG. 5.

When it comes to mounting the desired section of film in a card of the type described, the first operation is to die out the aperture as indicated diagrammatically in FIG. 6 in which a suitable punch 24 punches out the section 22 through an opening in the base 25 by which the card 5 is supported. As shown, the dimensions of the opening of the base and of the punch are such that the cut is made through the thin webs 20 around the section 22, leaving the major portions of these webs projecting into the aperture. Having thus formed the aperture, the desired section of film is then brought to the position shown in FIG. 7. Here the card 5 rests on a supporting

table 26 having an aperture of substantially the same size and shape as the card aperture bounded by the webs 20 which are overlapped by the edges of the film section. The film section is in direct contact with the coating 23 of adhesive material which is preferably applied to the ground areas of the back of the card as already stated. This preferred arrangement is shown in FIG. 7, wherein the film, comprising the usual base 27 coated with the usual emulsion 28 is positioned with its edges overlapping the coated webs 20. Pressure is then applied by means of any suitable pressure plate or die 29, with the result that the webs 20 and the film itself are forced downwardly in the aperture in the card to a position substantially as indicated in FIG. 8 in which the outer surface of the emulsion side 28 of the film is substantially flush with the upper surface of the card. At the same time the outer surface of the base 27 of the film is bonded to the underlying webs 20 by virtue of the rupture of the capsules under the applied pressure and consequent activation of the adhesive, and with accompanying thinning of the adhesive layer until said outer surface is substantially flush with the lower surface of the card for practical purposes. By way of example, the total thickness of the web (say 0.0015") and of the film (about 0.0055") is 0.007 inch which is within the prescribed tolerance limits of card thickness.

While only one embodiment of the invention has been specifically described and illustrated, it is to be understood that the invention is not restricted to this embodiment and that reference should be had to the appended claim for a definition of the limits of the invention.

What is claimed is:

A record card adapted to be apertured at a predetermined location for projectably mounting sections of microfilm and like projectable transparencies which comprises a flat relatively thin card of fibrous material of uniform thickness except for a thinner narrow elongated strip forming a trench-like depression which extends around the outline of the aperture to be formed in the card, said strip forming a web which connects the card section surrounded thereby with the outer sections of the card as an integral structure and said card sections and said strip all having a continuous and substantially identical fibrous structure, and a dry, solid, non-tacky, potentially adhesive material coating said strip in the bottom of said trench-like depression with its outer exposed surface below the plane of the card surface in which said depression is formed, said coating comprising a profusion of pressure-rupturable capsules containing materials releasable by fracture of said capsules and effective on release to tackify said coating.
